UNITED STATES PATENT OFFICE.

WALTER E. RATHBUN, OF MILAN, ILLINOIS.

DRIVE FOR CREAM-SEPARATORS.

1,281,418.

Specification of Letters Patent. Patented Oct. 15, 1918.

Application filed July 6, 1917. Serial No. 178,896.

To all whom it may concern:

Be it known that I, WALTER E. RATHBUN, a citizen of the United States, residing at Milan, county of Rock Island, and State of Illinois, have invented certain new and useful Improvements in Drives for Cream-Separators, of which the following is a specification.

The present invention has to do with certain improvements in mechanisms or devices for driving cream separators and the like, although it will presently appear that it may also be usefully applied for the driving of other devices than cream separators. However, I have shown the features of the present invention as applied to the driving of a cream separator as a matter of convenience, and also because the said features are peculiarly adapted to this particular class of service.

The bowls of a cream separator are driven at a very high rate of speed ranging ordinarily from six or seven thousand revolutions per minute to twenty or thirty thousand revolutions per minute. This makes it necessary to use a very high ratio of multiplication of speed in the gears since the driving crank or shaft will ordinarily run at from fifty to one hundred revolutions per minute.

The use of power drives for this class of work is coming rapidly into favor and particularly so in connection with the larger sizes of separators. Where the driving torque is perfectly uniform as in the case of an electric motor or the like, there is no difficulty encountered in the operation of the speed multiplication gearing, and where electric motors or the like are used power drives can be very satisfactorily applied.

This has not been true, however, as regards the application of power from a gas engine or similar prime mover in which there is a considerable variation of torque in different portions of the operating cycle. If the gas engines were to be directly connected to the main driving shaft of a cream separator, the gears of the separator would in all probability be stripped or damaged, because it would be impossible for the bowl to follow the tremendous changes of speed corresponding to the fluctuations in the speed of the gas engine multiplied by the gear ratio.

The present invention has to do with a construction of driving mechanism whereby the variations in the torque of the motor

can be instantly taken up by a spring or other resilient element, so that a practically constant driving effort is applied to the main shaft of the separator. Another feature of the invention has to do with the provision of a construction such that not only can the foregoing result be attained, but also the device may be used as an ordinary hand drive, when desired.

The torque or force which must be applied to the main shaft is generally an indication of the mechanical condition of the separator and its gearing. If the torque be abnormally large, there is an indication of undue friction or resistance either in the bowls or in the gears. This should be a danger signal to the operator and should cause him to investigate in order to locate the source of the trouble. Another feature of the invention has to do with the provision of a suitable indicator for showing momentarily and instantly the exact relative amount of torque being applied from time to time so that the operator has always before him an indication of the relative mechanical condition of the machine.

Other objects and uses of the invention will appear from a detailed description of the same which consists in the features of construction and combinations of parts hereinafter described and claimed.

Referring to the drawings:

Figure 1 shows in perspective a view of a simple form of cream separator having applied thereto a power drive embodying the features of the present invention;

Fig. 2 shows a back face view of the power driving arm and associated parts;

Fig. 3 shows a cross section partly in elevation of the construction shown in Fig. 2; and

Fig. 4 shows a detail section taken on the line 4-4 of Fig. 3, looking in the direction of the arrows.

Referring first to Fig. 1, the separator therein indicated is designated in its entirety by the numeral 5. It includes a main shaft 6 which communicates with the rotating bowls through a train of gearing contained in the stand 7. Inasmuch as I am not particularly concerned with the construction of a separator or this train of gearing, I will not further describe these features. Suffice it to state that the shaft 6 is the main shaft on which the power is to be applied.

Ordinarily a crank is applied to the main shaft 6 when the machine is to be driven by hand power. In order to permit of the use of the present device either by hand or power, I have provided a crank 8 having a handle 9. The construction of these parts is shown in detail in Figs. 2, 3, and 4. The crank is provided on its inner end with a hub 10 mounted on a stub shaft 11. This 10 stub shaft in turn has a socket 12 at its inner end to receive the protruding portion of the main shaft 6, to which the shaft 11 may be keyed as by means of a pin 13. On the extreme end of the stub shaft 11 is a 15 neck 14 onto which may be slid a collar 15 which may be pinned to the neck by means of a pin 16 so as to hold the hub 10 in place on the stub shaft.

Means are provided whereby when the 20 crank 8 is rotated, the stub shaft will be driven forward, but whereby when the stub shaft rotates under power drive, the crank remaining stationary, the stub shaft may run ahead of the crank. The particular 25 means illustrated for accomplishing this result includes a cam notch 17 formed in the stub shaft 11 receiving a pin 18 working in a recess of the hub 10 under the influence of a spring 19. The pin engages the abrupt 30 side of the cam notch, so that when the hub is rotated, the stub shaft will be driven, but the stub shaft can run ahead of the hub 10.

A gear 20 is keyed or otherwise secured to the stub shaft and rotates with the same. 35 A jack shaft 21 extends through a suitable journal in the crank 8, and a pinion 22 on the inner end of the said jack shaft meshes with the gear 20. On the outer end of the jack shaft is a pulley or other driving device 23 by which the power drive is applied 40 when desired. By rotating the pulley 23 in the direction of the arrows in Figs. 2 and 3, the main gear 20 will be driven in the forward direction as shown by its arrows.

45 Now when power is applied through the medium of the pulley 23 and jack shaft 21, there is a tendency for the pinion 22 to climb backward around the gear 20. This will create a tendency for the crank 8 to 50 rotate in the back direction, as shown by the arrow 24 in Fig. 2. This tendency of the crank to rotate must be resisted. Such resistance is secured through the medium of a spring in a scale 25, one end of which 55 scale is connected to a lug 26 on the crank 8, and the other end of which scale is connected to a stationary part 27 on the frame of the separator. The spring constitutes a yielding element which permits the crank 60 arm 8 to fluctuate or vibrate back and forth in order to take up momentary variations or changes in the driving torque, and the scale itself gives an indication as to the exact amount of torque being exerted. Ordinarily 65 the indication of the scale will be relative

only, its pointer showing whether the torque is greater or less than normal. If desired, the scale may give the reading directly in pounds or other units of force.

When the machine is being driven by 70 power a belt 28 may be conveniently passed over the pulley 23, or any other suitable driving connection may be effected, as by means of a chain or the like.

A cover or pan 29 having a peripheral 75 flange 30 is illustrated, the same covering the gears and serving to that extent to eliminate danger of accidents.

While I have herein shown and described only a single embodiment of my invention, 80 still it will be understood that I do not limit myself to the said embodiment except as I may do so in the claims.

I claim:

1. The combination with the main driving shaft of a cream separator, of a stub shaft connected thereto, a crank journaled on the said stub shaft, means for drivingly locking the crank to the stub shaft when the crank tends to run ahead of the stub shaft, 90 and for permitting the stub shaft to run ahead of the crank, a gear secured to the stub shaft, a jack shaft journaled in the crank, a pinion on the jack shaft meshing with the gear, a driving connection on the jack 95 shaft, a yieldable connection from the crank to a stationary part permitting the crank to yield resiliently when power is applied to the power drive connection, and an indicator in said yieldable connection for the 100 purpose specified.

2. The combination with the main driving shaft of a cream separator, of a crank, a driving connection from the crank to the driving shaft for driving said shaft when 105 the crank tends to run ahead of the shaft, and for permitting the shaft to run ahead of the crank, a main gear drivingly connected to the shaft, a jack shaft journaled in the crank, a pinion on the jack shaft meshing with the main gear, a driving connection on the jack shaft, and a resilient connection from the crank to a stationary part permitting the crank to yield under variations of torque for the purpose specified. 110

3. The combination with the operating mechanism of a cream separator, of a crank, a driving connection from the crank to said operating mechanism for transmitting a driving force from the crank to the operating 115 mechanism when the crank tends to run ahead of the operating mechanism and for permitting the operating mechanism to run ahead of the crank, a gear, an operative connection from said gear to the operating 120 mechanism, a jack shaft on the crank, a pinion on the jack shaft meshing with the gear, a driving connection on the jack shaft, and a resilient connection from the crank to a stationary part permitting the crank to 125 130

yield under variations of driving force, for the purpose specified.

4. The combination with the operating mechanism of a cream separator, of a swinging arm, a driving connection from said arm to the operating mechanism for transmitting a driving force from the arm to the operating mechanism when the arm tends to run ahead of the operating mechanism, and 10 for permitting the operating mechanism to

run ahead of the arm, a gear drivingly connected to the operating mechanism, a pinion carried by the arm and meshing with the gear, a driving connection for said pinion, and a yieldable connection from the arm to a 15 stationary part permitting the arm to swing under variations of driving force, for the purpose specified.

WALTER E. RATHBUN.
